UNITED STATES PATENT OFFICE.

CHARLES E. MYERS, OF ST. LOUIS, MISSOURI, ASSIGNOR, BY DIRECT AND MESNE ASSIGNMENTS, OF ONE-HALF TO JOHN WEILACHER AND ONE-HALF TO THOMAS J. LAVIN, WILLIAM A. RHEINHEIMER, AND GUS BAUER, ALL OF ST. LOUIS, MISSOURI.

METHOD OF FORMING STITCHES.

1,252,150.

Specification of Letters Patent.

Patented Jan. 1, 1918.

Application filed March 29, 1917. Serial No. 158,298.

To all whom it may concern:

Be it known that I, CHARLES E. MYERS, a citizen of the United States of America, and a resident of the city of St. Louis, State of Missouri, have invented a certain new and useful Improvement in Methods of Forming Stitches, of which the following is a specification.

This invention relates to the formation of seams for stitched articles of leather or heavy material, and more particularly to the stitching of the soles of shoes.

The prime object of the invention is to afford a method of stitching resulting in a seam which, in distinction to the stitch shown in United States Patent No. 1,114,533 issued to me and G. S. Savignac on Oct. 20th, 1914 and to other prior patents of the same general character, cannot be ripped or unraveled, whereby a shoe, a set of harness, a valise, a raincoat or other article subjected to constant hard wear will be rendered more durable and thus more satisfactory to the purchaser.

In sewing together the plies of leather (or other material) forming the sole of a shoe it is now the custom to employ a continuous stitch commonly termed a "loop-lock" which is projected through each loop of the vertically inserted stitching-thread for the purpose of resisting the tendency of the plies to spring apart after said thread has been worn or broken.

While effective to a degree, stitching of this character still leaves much to be desired, for it will be appreciated that, as the so-called loop-lock is continuous or, in other words, formed throughout the length of the seam by carrying forward and looping a single thread, the constant flexing of the shoe tends to pull the lock out of the needle-thread loop and thus permits the eventual disintegration of the entire seam. The correction of this defect has long been sought by those familiar with the situation and is the distinguishing feature of the present invention.

In the accompanying diagrammatic drawing, which is greatly enlarged and wherein like numerals refer to like parts throughout the several views, Figure 1 depicts the vertically inserted stitching-thread carried through a uniform awl-made puncture in

two layers of material which may here be regarded as the inner and outer plies of a shoe sole; Fig. 2 depicts the loop-locking thread projected through the loop of the stitching-thread, this being the second step in the formation of the stitch; Fig. 3 depicts the third step in the process, namely, the projection of a separate thread of stout material between the strands of the loop-lock in advance of the stitching-thread; Fig. 4 the next step, namely the drawing upward of the stitching-thread; Fig. 5 the fifth step of the process consisting of the retraction of the loop-lock against the individual thread first shown in Fig. 3; Fig. 6 the final step, namely the drawing of the knot formed by the preceding steps into the awl-made puncture; and Fig. 7 a bottom plan view of the step shown in Fig. 4.

In carrying the invention into practice, the material operated upon is first punctured by an awl moving in advance of the needles to form a uniform puncture 1 and the stitching-thread 2 is then fed therethrough and returned to provide a loop 3. The continuous thread 4 is next projected by suitable mechanism through the loop 3 and returned to form the loop 5, commonly termed the "locking-loop," and thereafter a reciprocating needle inserts the strand 6 through loop 5 in advance of loop 3 and in close relation thereto. These steps having been accomplished a cutting device is automatically brought into play to sever strand 6 on both sides of loop 5; next the threads 2 and 4 are successively retracted (as shown in Figs. 4 and 5) by take-up mechanism; and finally the knot formed by the juncture of loop 5 and strand 6 is drawn upward, by the continued action of said mechanism, into the puncture 1 and thus protected from wear.

From the foregoing it will be appreciated that the severance of strand 6 between each puncture results in the provision of what may aptly be termed a "bar-lock" between each stitch of the sewing needles, and that (in distinction to the continuous loop-lock heretofore employed) it is impossible to rip or unravel such a seam and the retention together of the plies of leather or other material would not be affected by wearing of the stitches at any one point.

Having thus fully described the invention, what I claim as new and desire to secure by Letters-Patent is:—

1. The method of forming a stitch which comprises the projection of a thread through a puncture in the layers of material to be united, forming a loop upon the opposite side of said material, passing through said loop a loop of another thread, inserting 5 through the second loop in advance of the loop first formed a third or locking thread, next severing the locking thread on either side of said second loop, and finally drawing the loops of said threads into said puncture.
- 10 2. The method of forming a stitch which comprises the projection of a thread through

a puncture in the layers of material to be united, forming a loop upon the opposite side of said material, passing through said loop a loop of another thread, inserting 20 through the second loop in advance of the loop first formed a third or locking thread, next severing the locking thread on either side of said second loop, subsequently successively retracting the first and second 25 loops, and finally drawing the loops of said threads into said puncture.
